US00D867112S

(12) **United States Design Patent** (10) **Patent No.:** **US D867,112 S**
(45) **Date of Patent:** **** Nov. 19, 2019**

(54) **BRACKET**

(71) Applicant: **Andrew A Taylor**, Assonet, MA (US)

(72) Inventor: **Andrew A Taylor**, Assonet, MA (US)

(**) Term: **15 Years**

(21) Appl. No.: **29/600,762**

(22) Filed: **Apr. 14, 2017**

(51) LOC (12) Cl. **08-05**

(52) U.S. Cl.

USPC **D8/363**

(58) **Field of Classification Search**
